UNITED STATES PATENT OFFICE

90,701

DESIGN FOR A TUMBLER

Charles M. Evans, Sapulpa, Okla., assignor to
Bartlett-Collins Company, Sapulpa, Okla., a
corporation of Oklahoma

Application May 2, 1932. Serial No. 43,688

Term of patent 3½ years

To all whom it may concern:

Be it known that I, CHARLES M. EVANS, a citizen of the United States, residing at Sapulpa, Creek County, in the State of Oklahoma, have invented a new, original, and ornamental Design for Tumblers, of which the following is a specification, reference being had to the accompanying drawing, forming a part thereof, and in which the figure is a side elevational view of a tumbler showing my new design. The contour of the tumbler is circular. The design comprises the arrange-

ment of panels of different sizes and intersecting horizontal and vertical bands, the horizontal bands near the top and bottom edges of the tumbler.

I claim:

The ornamental design for a tumbler, substantially as shown and described.

In witness whereof, I have hereunto set my hand.

CHARLES M. EVANS.
